[57] **ABSTRACT**

An egg-accumulating table which reduces the surface area of the surface engaging the eggs by utilizing endless wirelike belts of narrow dimension. To further reduce the forward pressure exerted by the supporting wirelike belts, every other belt is returned in the same supporting plane in which it moves forward, so as to present to the eggs as every third belt, one which is moving in the opposite direction. The reversal is accomplished by utilizing a separate roller which every other belt returns to after reaching the delivery end, and a separate roller over which every other belt departs the supporting plane before reaching the initiating end of the table.

ACCUMULATING TABLE FOR EGG PACKER

BACKGROUND OF THE INVENTION

Egg-packing apparatus such as that disclosed in U.S. Pat. No. 3,311,216 require accumulating devices to insure that a constant stream of eggs is flowing into the orientation part of the machine and to allow groups of eggs to be deposited for feeding to the machine. The problem in the past has been that the accumulating devices, in order to maintain sufficient pressure so as to maintain the feed to the egg-packing apparatus, have either caused eggs to pile up at the entrance to the packing apparatus or have required expensive and elaborate devices for preventing such pileups. The pileups are undesirable because eventually the eggs start spilling over the machine resulting in breakage. Eggs pile up and fall back down on other eggs causing checks, cracks and breaks.

On the other hand, if the pressure of the eggs being fed into the machine is reduced so that there is no pileup, very often the pressure will be insufficient to maintain feed whenever openings occur in the packing apparatus.

SUMMARY OF THE INVENTION

The invention relates to an accumulating table for supplying eggs to an egg-packing apparatus without piling up the eggs. Specifically, the invention concerns such an accumulating table comprising a supporting surface in contact with the egg restraining means for preventing eggs from falling off the sides of the table, and reducing means for reducing the area of the supporting surface in contact with the eggs, the reducing means including means for providing to the eggs a resultant direction of movement with respect to the preventing means. The latter includes means for urging eggs in a direction parallel with respect to the preventing means and at least one of a plurality of wirelike belts which form the supporting surface and are included in the reducing means.

Accordingly, it is an object of the invention to provide an accumulating table which will simply and efficiently supply eggs constantly to an egg-packing apparatus without piling up the eggs at the point of entry into the machine.

It is a further object of the invention to provide a table of the above character which is inexpensive to produce and easy to operate.

It is a related object to provide a table of the above character in which columns confining the eggs are initiated without causing a buildup of eggs in the columns.

Other objects and advantages will become apparent upon reference to the following drawings and detailed discussion.

BRIEF DESCRIPTION OF THE DRAWINGS

FIG. 1 is a perspective view, partially broken away, illustrating a portion of the accumulating table constructed in accordance with the invention;

FIG. 2 is an end view in perspective illustrating the table of FIG. 1 in conjunction with the dejammer plow;

FIG. 3 is a schematic sectional view illustrating the supporting wirelike belts of the accumulating table;

FIG. 4 is a fragmentary perspective view of a holdown cover utilized in conjunction with the dejammer plow;

FIG. 5 is a fragmentary plan view of the table illustrated in FIG. 2;

FIG. 6 is a fragmentary side elevational view partially broken away, illustrating part of the drive of the dejammer plow; and

FIG. 7 is the same view as shown in FIG. 6 except that the remainder of the drive is shown.

DESCRIPTION OF THE PREFERRED EMBODIMENT

The invention provides an accumulating table for supplying eggs to an egg-packing apparatus (not shown), the latter being for example the apparatus disclosed in U.S. Pat. No. 3,311,216 or which may be the apparatus disclosed in my copending application Ser. No. 863,893 filed Oct. 6, 1969,

which latter is commonly owned with this application. The structure of the egg-packing apparatus itself is not critical with respect to this invention, it being only necessary to supply the eggs from the table of the invention whenever an opening occurs in the egg-packing apparatus, such as when the eggs are advanced one step at a time in the packing apparatus. Such continual feeding requires a backup of eggs on the accumulating table, and it is the control of this backup which I have accomplished with the invention.

10

ACCUMULATING TABLE

In accordance with the invention, the accumulating table comprises a frame 20 having two sidewalls 22 to prevent eggs from falling off the sides, a drive roller 24 mounted at the end of the table 20 which feeds to the egg-packing apparatus, an idler roller 26 at the opposite end of the accumulating table, and two other idler rollers 28 and 29 located beneath the drive roller 24 and the idler roller 26, respectively. To drive the drive roller 24, a sprocket 31 is mounted on the end thereof and is driven via a chain by a motor 33. To reduce the amount of surface friction engaging the eggs, the egg-supporting surfaces of the table is formed by a plurality of wirelike belts 30 rather than a fully extended fabric. The belts are endless with a circular cross section, and individually comprise belts 32, 34, 36, 38 and 40, there being others utilized but not labeled so that the entire table is covered by the belts as shown for example in FIG. 5. The belts can be formed of any material, one example being urethane strings of $\frac{1}{8}$ -inch diameter. To give support to the belts as the eggs are carried along the table from one end to the other, support rollers 42 roll on pins in holes in the sidewalls 22 just under the plane formed by the rollers 24 and 26. The rollers preferably have a vinyl cover thereon.

35

To carry the eggs from the end of the table defined by idler roller 26 to the end of the table defined by the driven roller 24 where they accumulate, the endless belts 32, 34, 36, 38 and 40 are rotated from right to left as seen in FIG. 1, and with respect to the sidewalls, and carried over the support rollers 42. The driving of the wirelike belts is accomplished by the engagement of drive roller 24 with the belts.

To reduce the pressure urging the eggs toward the drive roller 24, means are included for returning every other belt back to the end of the table defined by idler roller 26 above the stationary bars 42 so that every third belt forming the egg-engaging surface is reversed, that is, driven in a direction opposite to the direction to the motion of the other belts. Thus, as seen in FIG. 1, belts 34 and 38 are not returned under the support rollers 42 as are the belts 32, 36, and 40, but rather they are returned in the same plane above the support rollers 42 in which they came. Belt 34 thus returns as a portion 34a which travels in the direction opposite to the direction in which the remainder of the belt 34 is traversing, while belt 38 returns as a portion 38a in the direction opposite to the direction in which the remainder of the belt 38 is passing. I have found that the reversal of motion of every third belt forming the egg-engaging surface prevents the eggs from piling up in the undesired fashion. To accomplish this reversal of every other belt in the egg-engaging surface, idler rollers 50 and 52 are spaced in the plane of the rollers 24 and 26 but within the rectangle defined by those rollers and the sidewalls 22. Thus, when belt 34 moving from right to left passes over drive roller 24 and the idler 28, instead of returning under the support rollers 42 it is wound around the idler roller 28 more than 90° so as to return as portion 34a to the plane of the egg-engaging surface. That belt is then partially wound around idler rollers 50 and 52 before engaging the idler roller 29 and the idler rollers 26 in that order. The same operation occurs with the belt 38.

The idler rollers 28, 30, 50 and 52 may be smooth, or as shown in FIG. 3, they may include circumferential recesses 54 to insure that there will be prevented any side slippage of the belt portion passing in the opposite direction, such as belt por-

75

tion 34a. I have found that in either form, the idler rollers maintain the proper spacing of the endless belts so as to insure that eggs do not fall therethrough. It will be readily appreciated by one skilled that to that end the endless belts must be spaced relatively close together, one example being one-fourth inch between belts as they pass over the support rollers 42, every third belt being spaced from the next or fourth belt by one-half inch, producing groups of threes. (See FIG. 2.)

DEJAMMER PLOW AND HOLDDOWN COVER

10

To initiate the formation of columns at the delivery end of table 20, a dejammer plow 62 forming entrance columns 64 by the partitions 66 thereof reciprocates vertically by means of a sidebar 68 which rides on a cam 70 driven by an extension of drive roller 24 comprising a shaft 72, a sprocket mounted thereon, and a chain 76 operating from a second sprocket 78 mounted on shaft 24. This prevents eggs designated as "E" from jamming sideways in their entrance into the machine. It is within this area of the dejammer plow that the eggs tend to pile up. That is, the eggs leading to the aisles tend to pile up even before they enter the aisles. To prevent this last tendency, a cover 80 is cantilevered from a bar 82, one end of which has attached an arm 84 which rests on a microswitch so as to close the same. When buildup occurs under the cover 80, it rises, thereby rotating the bar 82 so as to lift the arm 84 from the microswitch. Opening the switch shuts down the machine, notifying the operator that a defective situation exists.

In addition, the eggs tend to pile up in aisles 64 even though the plow insures that they are not jammed in sideways. To prevent buildup of eggs within the dejammer plow, a hold-down cover 90 is utilized in conjunction therewith. The cover comprises a support bar 92 extending the full width of the table, an extension 94 thereof resting on one sidewall 22. To hold down eggs which have moved into the columns formed by the plow 62, plates 96 (FIG. 4) are spring-biasedly attached to the support bar, springs 98 allowing the plates to rise vertically. Each plate and spring is cantilevered separately from the bar to fit its appropriate column. To limit the upward movement of each plate 96, a screw 100 is passed through the support bar above each plate. The adjustment of the screw allows the plates's upward movement to be increased for larger sized eggs.

OPERATION

Because of the resultant movement of the eggs from idler roller 26 to the driving roller 24, eggs placed on the table 20 will be urged to feed into the dejammer plow 62 and thence into the egg-packing apparatus. Because wires or belts are used to form the supporting surface, there is a reduction in the friction provided to the eggs. This reduction of friction is further accomplished by bringing back every other belt on top of the plane formed by the rollers 42 rather than below it, so that the eggs encounter as every third supporting belt a belt going in the opposite direction. The holddown cover keeps the

eggs from piling up in the dejammer plow.

The embodiments of the invention in which an exclusive property or privilege is claimed and defined as follows:

1. An accumulating table for supplying eggs to an automatic egg-packing machine having an egg-supporting surface in contact with the eggs and restraining means for preventing eggs from falling off said surface at the sides of the table the improvement in said supporting surface comprising:
a plurality of wirelike members located between said restraining means and extending substantially parallel thereto, said members being spaced apart a distance less than the smallest dimension of the eggs, and forming an unobstructed egg support surface;
motive means driving at least some of said members in a first direction to urge the eggs in a direction parallel with respect to said restraining means while simultaneously moving others of said members in an opposite direction for providing to the eggs a resultant direction of movement with respect to said restraining means and to prevent the eggs from piling up on the table.
2. The table as defined in claim 1, wherein said members are endless wirelike belts.
3. The table as defined in claim 2, wherein all of said endless wirelike belts are mounted for endless driving between said restraining means, said motive means including a drive roller at one end of said table engaging all of said belts; and further including stationary bars over which said some of said belts return, and under which said others of said belts return.
4. The table as defined in claim 3, and further including means for reversing said some of said belts so that it passes over said stationary bars in both directions of movement with respect to said restraining means.
5. The table as defined in claim 4, wherein said reversing means includes an idler roller spaced from said drive roller around which every other belt is partially wound; and a second idler roller rotatably mounted below said drive roller; said every other belt being wound more than 90° around said second idler roller.
6. The table as defined in claim 5, wherein said idler rollers include means for preventing any side slippage of said every other belt along said idler rollers.
7. The table as defined in claim 6, wherein said means include circumferential recesses in said idler rollers.
8. The table as defined in claim 3 wherein said motive means include means for driving said some of said belts above said bars in a direction opposite to the direction of motion of the remaining belts above said bars.
9. The table as defined in claim 8, wherein said driving means includes a first idler roller spaced from said drive roller around which every third belt passing above said bars is partially wound, and a second idler roller rotatably mounted below said drive roller, said every third belt being wound more than 90° around said second idler roller prior to its engagement with said first idler roller.
